UNITED STATES PATENT OFFICE.

MARK SHOELD, OF CHICAGO, ILLINOIS, ASSIGNOR TO ARMOUR FERTILIZER WORKS, OF CHICAGO, ILLINOIS, A CORPORATION OF NEW JERSEY.

APPARATUS FOR CALCINING PHOSPHATE ROCK.

1,393,840.

Specification of Letters Patent.

Patented Oct. 18, 1921.

Application filed February 24, 1920. Serial No. 360,959.

To all whom it may concern:

Be it known that I, MARK SHOELD, a subject of the King of Sweden, residing at Chicago, in the county of Cook and State of Illinois, have invented certain new and useful Improvements in Apparatus for Calcining Phosphate Rocks, of which the following is a specification.

It has been proposed, heretofore, to calcine ground natural phosphate-rock to render the phosphate available in ammonium-citrate soluble form by gradually heating to the required temperature a mixture of such finely-divided rock and sodium acid sulfate, or other suitable salt, in a furnace of proper construction, such as an inclined, internally-fired, rotary kiln. I have discovered, however, that if the ground mixture to be treated is gradually or relatively-slowly heated to the required reaction temperature, as has heretofore comprised the suggested procedure, as by introducing the mixture at the upper end of a comparatively-long, inclined kiln, and permitting it to progressively travel down the kiln, a preliminary, undesired or detrimental lumping up or sintering of the material takes place, which lowers in substantial degree the percentage of the material converted into available form at the higher temperature of the conversion reaction. Apparently, the treated material is subject to two sintering actions, one at a lower temperature from which no good results, representing in fact an objectionable feature, and one at the higher temperature at which the conversion takes place. In accordance with a new and improved process of mine, covered by my co-pending patent application, Serial No. 360958, filed February 24, 1920, whereby the material is suddenly and almost instantaneously heated to the reaction temperature, the objectionable detrimental results of the first sintering are in large measure, if not entirely, overcome, or, stated somewhat otherwise, the heating of the material is so quick and rapid that the lower critical sintering temperature is passed without the injurious or wasteful sintering occurring to any objectionable degree. In carrying out this process in its preferred form, a slurry stream of the material to be treated is played by means of a suitable nozzle in a smooth and unbroken stream

directly into the heat or reaction zone of the furnace or kiln, whereby the material is subjected to a very sudden heating, the water possibly being quickly converted into steam, and thus, by its more or less explosive action preventing a lumping up or coalescing of the particles at the lower sintering temperature, the presence of the steam also facilitating and assisting the conversion reaction at the higher temperature.

The present invention relates to an apparatus for carrying out this novel calcining process or method, the prime purpose of the invention being the provision of a simple, inexpensive, but efficient appliance by which this process may be practised commercially and economically.

In order that those skilled in this art may have a full and complete understanding of an apparatus incorporating the features of this invention, in the accompanying drawings, I have illustrated a preferred and desirable embodiment of the same in more or less diagrammatic form.

In these drawings, in which like reference characters refer to the same parts in the two views,

Figure 1 is a central, vertical section through the rotary inclined kiln; and

Fig. 2 is a horizontal section above the kiln.

By reference to the drawings, it will be understood that the apparatus comprises an ordinary, but rather short, inclined, internally-fired, rotary kiln 10 supported on rollers 11, 11 mounted on suitable pillars 12, 12 and revolved in the usual way by a gear 13 driven by a pinion 14 on the top of a central pillar 15 and revolved by any suitable source of power, not shown. Convenient dimensions for such a rotary cylinder or kiln are 7 feet in diameter and sixteen feet in length with a substantial pitch, as shown, for the relatively-quick delivery or discharge of the material.

The open ends of the kiln are in direct communication with spaced parallel chambers or compartments 16 and 17 formed by suitable walls made of heat insulating material, such as fire-brick 18, silocel 19, and common brick 20. These chambers or flues 16 and 17 have aligned angle extensions 21 and 22, separated from one another by a division or partition wall 23, constituting dust

collecting or settling chambers, the upper end of the compartment 16 being connected to the top portion of a checker-work or flue construction 24 which in turn is connected 5 at its lower end to the corresponding portion of the next checker-work or flue section 25, and this in turn is connected at its upper end to the top of a third checker-work or flue structure 26, the latter by means of a flue or 10 passage 27 being operatively associated with a reversing-valve 28 connected to a stack 29. By means of like checker-work or multiple flue structures 30, 31, and 32 and a flue 33, the other or companion chamber 17 is connected 15 to the valve.

This general structure is an ordinary regenerator system which does not require detailed description or illustration and is used in the customary way in conjunction with 20 the usual motor-driven blower and exhauster, not shown, to heat the air passing through the kiln to conserve heat.

The inclined kiln at each end is supplied with a burner, 34 and 35 respectively, extended through the outer wall of the corresponding chamber or compartment 16 or 17, such burners being supplied with oil and steam in the usual way or, if preferred, gas or powdered coal may be used as the fuel. 30 As will be readily understood, first one burner is operated and the heated air supplied through one portion of the regenerator system, the products of combustion passing through and heating the checker-work of the complementary portion of the regenerator on their way to the stack. Then such first burner is shut off, the second one set in 35 operation, and the regenerator valve manipulated to reverse the air and combustion 40 gas flow. Such alternating use of the burners is continued and may be effected manually or automatically.

The more important part of the appliance comprises a water-jacketed nozzle 36 extended into the chamber 17 through its outer wall and in line with the lower end of the kiln, such nozzle being hinged or pivoted at 37 in any approved fashion, whereby the stream delivered therefrom into the kiln 45 may be caused to take different positions in the heat zone thereof, that is to say, the stream may be shifted or changed throughout the length of the heat or reaction zone by modifying the position of the nozzle. 50 The slurry of a consistency, for example, of from 45 to 55 degrees Baumé, and containing ground natural phosphate-rock and sodium acid sulfate, in the approximate proportions of 100 parts by weight of the 55 former to about 20 to 30 parts of the latter, is fed to the nozzle under pressure by any suitable means, as by air-pressure, and from the nozzle it is projected directly and quickly into the central heat zone or reaction part 60 of the kiln in a smooth, substantially solid, 65

unbroken or undivided stream. This quick and sudden introduction of the material to be calcined into the heat zone of the kiln maintained at a temperature of approximately 1100 degrees to 1400 degrees centigrade, causes a very abrupt and sudden change of temperature of the material so that there is practically no lumping up or sintering of it until it reaches the reaction temperature, when the phosphate is quickly 75 converted into ammonium-citrate soluble form.

The water of the stream, possibly by its quick conversion or expansion into steam, prevents in large measure, if not entirely, 80 the lumping up or sintering of the material undergoing treatment at the lower critical or crucial sintering temperature, and the presence of the steam at the higher reaction temperature facilitates and aids in the 85 chemical transformation.

The nozzle is so shaped and formed that the slurry stream delivered therefrom is in practically solid condition, thus preventing any spraying or subdivision of the stream 90 which might carry some of the material into those parts of the furnace where it would not be heated with the required rapidity to assure a maximum percentage of 95 available phosphate.

By moving or rocking the position of the nozzle, the stream may be caused to play into different portions of the central heat zone, thus employing the apparatus to maximum advantage and securing the best and 100 most economical effects with the heat developed, at the same time avoiding any undue cooling action in any particular part of the kiln.

In about 10 to 15 minutes after its introduction in slurry form into the furnace, any particular portion of the material treated is delivered or discharged from the lower end of the kiln and is desirably ground for use.

In this application I have illustrated and 110 described an inclined, internally-fired rotary kiln, but the particular style and form of furnace is more or less immaterial and the type shown is by way of example only and may be modified to a considerable extent or 115 degree and still be employed satisfactorily for the performance of the specified process.

It has also been indicated that the material to be treated is introduced in the form of a slurry stream, but in some cases it may possibly be injected into the heat chamber in dry form, but the losses due to the finely-divided material being carried along by the gaseous or air current might be objectionable.

One of the vital and essential features of the invention is an apparatus by which the material to be treated may be heated almost instantaneously, such as by suddenly introducing it into the heat zone, so that its tempera- 136

ture will be very rapidly increased and the critical temperature quickly passed to prevent wholly or in part any detrimental action such as sintering or coalescing of the particles before the reaction temperature is attained.

It will be appreciated, therefore, that the invention is not limited and restricted to the precise and exact structural features shown and described, since these are capable of radical modifications without departure from the substance and essence of the invention and without the sacrifice of any of its substantial benefits and advantages. For instance, although the rotary kiln has been shown with a burner at each end in association with a regenerator system, those skilled in this art will understand that a kiln could be employed with a burner at one end only and without any regeneration.

I claim:

1. In a calcining structure of the character described, the combination of a furnace, and means to introduce a slurry stream 25 of the material to be treated under pressure directly into the reaction heat zone of such furnace sufficiently suddenly to prevent any substantial detrimental preliminary heat action on the material, substantially as described.
2. In a calcining structure of the character described, the combination of a furnace, and means to introduce a slurry stream 35 of the material to be treated directly into the reaction heat zone of such furnace sufficiently suddenly to prevent any substantial detrimental preliminary heat action on the material, and means to vary the position of such stream, substantially as described.
3. In a calcining structure of the character described, the combination of a rotary inclined kiln, and means to introduce the material to be treated in the kiln through its lower end, substantially as described.
4. In a calcining structure of the character described, the combination of an internally-fired rotary inclined kiln, and means to introduce the material to be treated in the

kiln through its lower end, substantially as described.

5. In a calcining structure of the character described, the combination of an internally-fired rotary inclined kiln, and means to project the material to be treated in the kiln rapidly through its lower end, substantially as described.

6. In a calcining structure of the character described, the combination of an internally-fired rotary inclined kiln, means to project the material to be treated in the kiln rapidly through its lower end, and means permitting variation of the position of said projecting means, substantially as described.

7. In a calcining structure of the character described, the combination of an internally-fired rotary inclined kiln, and a nozzle directed into and adapted to deliver the material to be treated directly into the reaction heat zone of the kiln, substantially as described.

8. In a calcining structure of the character described, the combination of an internally-fired rotary inclined kiln, and a nozzle extended through the lower end of the kiln and directed to deliver the material to be treated directly into the reaction heat zone of the kiln, substantially as described.

9. In a calcining structure of the character described, the combination of an internally-fired rotary inclined kiln, and a movable nozzle constructed and positioned to deliver a relatively-smooth, comparatively-undivided slurry stream directly into the reaction heat zone of the kiln, substantially as described.

10. In a calcining structure of the character described, the combination of an internally-fired rotary inclined kiln, and a movable nozzle constructed to project a relatively-smooth, comparatively-undivided slurry stream of the material to be treated through the lower end of the kiln directly into the reaction heat zone thereof, substantially as described.

MARK SHOELD.
